HANS OTTO STORM, OF PALO ALTO, CALIFORNIA, ASSIGNEE TO FEDERAL TELEGRAPH COMPANY, OF SAN FRANCISCO, CALIFORNIA, A CORPORATION OF CALIFORNIA.

ARC GENERATOR ELECTRODE.

Application filed January 5, 1927. Serial No. 152,145.

This invention relates generally to electrodes suitable for use in arc generators which are used in producing high frequency electrical oscillations.

5 Arc generators generally utilize two or more electrodes enclosed within a chamber. For controlling the generation of oscillations, it is necessary to adjust the length of the gap, and for this purpose at least one of the electrodes is provided with an adjustable mounting. Cooling is effected by circulating fluid such as water, through passageways in the electrode. In addition to providing a longitudinal adjustment for one of the electrodes, 10 it is desirable to be able to bring the electrodes into contact with each other for striking an arc.

It is an object of this invention to devise a fluid cooled electrode which is continuously 20 rotated about its axis.

It is a further object of this invention to provide fluid cooling for a continuously rotated arc electrode which will make it impossible for fluid leakage to occur within the 25 arc chamber.

It is a further object of this invention to devise a novel form of rotatable fluid cooled arc electrode which may be adjusted longitudinally and independently shifted inwardly of the arc chamber to strike an arc.

Further objects of this invention will appear from the following description in which I have set forth the preferred embodiment of my invention. It is to be understood that 35 the claims are to be accorded a range of equivalents consistent with the state of the prior art.

Referring to the drawings:

Figure 1 is a transverse cross sectional view showing an arc electrode constructed in accordance with this invention and extending through the wall of an arc chamber.

Figure 2 is a cross sectional view taken along the line 2—2 of Fig. 1.

45 Fig. 3 is a detail view taken along the line 3—3 of Fig. 1.

Figure 4 is a wiring diagram showing diagrammatically the manner in which the arc electrodes are associated with the electrical 50 circuit.

The invention comprises generally an arc electrode insertable through the wall of an arc chamber and which is adapted to be continuously rotated about its axis. For adjusting the length of the arc gap during

normal operation suitable means is provided exteriorly of the chamber for advancing or retracting the electrode. The electrode is mounted in the wall of the chamber in such a manner that by applying force to its external portion it may be moved inwardly against the tension of a spring to bring the same into contact with another electrode and thus strike an arc. Fluid for cooling purposes is continuously circulated through passageways in a stationary external head by means of which the fluid is conducted to the tip of the electrode. The entire electrode structure may be removed as a unit from the chamber to permit inspection or repair. 60 65 70

Referring to the specific embodiment of the invention illustrated in the drawings, there is shown an electrode structure 10 insertable through the wall 11 of an arc generator chamber. The electrode structure includes a rotatable body member 12 to the inner end of which is secured an electrode tip 13, this tip being preferably of metal although it may be of other substances such as carbon. The tip 13 is detachably secured 75 to the body member 12 by suitable means such as the coupling 14, so that it may be removed for replacement. The intermediate portion of the body member 12 is slidably fitted into an outer shell 16, the body member being 80 provided with a key 17 engaging a slot 18 in the shell 16 so that both body member and shell will rotate together. The inner portion of the shell 16 is also splined to a power driven sleeve 19, as by means of a key 20 85 90 95 slidably fitting a groove 21 in the shell 16. Sleeve 19 is journaled in a bore 23 provided in the extension 24 of the chamber wall 11, and is driven by suitable means such as a motor shaft 26 carrying the worm 27 engaging a worm gear 28 formed upon the periphery of the sleeve. The shell 16 is further journaled in a ring 29 which is slidably disposed in the bore 30.

The sliding fit between the shell 16 and the sleeve 19 and between ring 29 and the bore 30 is intended to permit limited longitudinal movement of the body member 12 for the purpose of moving the arc electrode tip 13 a limited amount to strike the arc. The 100 arc electrode is always returned to its original position after being shifted inwardly by means of a compression spring 32 tending to urge the ring 29 outwardly, the shell 16 being provided with a suitable annular shoulder 105 110

33 against which the ring 29 normally abuts. The electrode structure is retained within the bore 30 by means of a latch member 34 pivotally mounted to the chamber wall as at 36 5 and biased by means of spring 37 to normally remain in engagement with the outer face of the annular shoulder 33. By pushing downwardly upon the latch 34 the sleeve 16 together with the body member 12 and its associated parts may be removed from the chamber.

The arc electrode is adjusted by moving the body member 12 relative to the shell 16. While a variety of expedients may be employed for this adjustment the particular mechanism shown includes a rotatable wheel 38 coupled to the outer end of the shell 16, and having a threaded engagement with the outer portion of the body member 12. For example, the wheel 38 is shown as having a threaded engagement with an externally threaded nut 39. An annular shoulder 41 upon the wheel 38 is adapted to engage an annular flange 42 upon the end of the shell 16 whereby the wheel is coupled to the shell in such a manner as to permit rotation thereto. A set screw 43 serves to retain the nut 39 within the wheel 38 until it is desired to take the electrode structure apart for repair. The nut 39 is also internally threaded to engage threads 44 upon the external portion of body member 12. Therefore, when wheel 38 is manually rotated relative to body member 12 and to the shell 16, the body member 12 will be advanced into the chamber or retracted, depending upon the direction of rotation of the wheel.

Fluid is admitted to the electrode structure for cooling the tip 13 by means of a non-rotatable head 46 to which are connected the fluid inlet and discharge pipes 47 and 48 respectively. A coupling connection is provided for connecting the non-rotatable head 46 and the external end of the rotatable body member 12, this coupling member comprising for example a sleeve 49 having threaded engagement with the head 46 and provided with an annular shoulder 51 engaging an annular flange 52 upon the external end of body member 12. In order to prevent leakage of fluid between body member 12 and the head 46 a packed joint is provided for the coupling between these members. The packed connection in this instance includes a tube 54 having its one end fixed with respect to the head 46 and having its inner end journaled within a bore 56 provided in the body member 12. An enlarged bore 57 in the outer portion of body member 12 provides a space about the tube 54 for packing 58. The bearing surface between the head 46 and the body member 12 is increased by providing an extended collar 59 upon the inner face of head 46, the inner face of this collar being adapted 65 to bear upon a ring 61 inserted between the

collar and the adjacent end of the packing 58.

Circulation of cooling fluid to the electrode tip is provided for by a fluid pipe 62 secured at its outer end to the head 46 and 70 communicating with the inlet pipe 47 by means of passageways 63 and 64. This pipe extends through tube 54 and bore 66 in body member 12 and bore 67 in electrode 13, these bores being substantially larger in diameter 75 than the diameter of pipe 62. Tube 54 is in communication with the discharge pipe 48 through passageways 68 and 69 in the head 46. Fluid, such as water, entering through pipe 47 will therefore be discharged through 80 pipe 62 upon the inner end of the electrode tip 13 and will then pass back through bores 67, 66 and tube 54 to the discharge pipe 48. In Fig. 4 I have shown a conventional form 85 of arc generator system with which the electrode described above may be incorporated. Thus the rotatable electrode 10 and another electrode 9 have been shown as disposed within an enclosed chamber 71, which usually contains a gaseous atmosphere such as hydrogen 90 or a hydrocarbon gas. Current is supplied to the electrode from suitable means such as a direct current generator 72, this generator also serving to energize the magnetic field 73. An oscillation circuit 74 is coupled to the 95 electrode in any of the well known ways.

In operating the device the arc may be initially struck by forcing the head 46 inwardly to move electrode tip 13 into contact with the other electrode of the arc. After an arc 100 has been established the head is released to permit the body member 12 and electrode tip to return to normal position. The electrode tip is continuously rotated by the drive shaft 26 which applies power to body member 12 105 through sleeve 19 and shell 16. Water or other cooling fluid is circulated through the relatively stationary head 46 by means of pipes 47 and 48, the fluid being discharged upon the electrode tip through pipe 62. Adjustment of the normal position of the electrode is secured by rotation of wheel 38 relative to body member 12 and shell 16 by means 110 of which the body member 12 is advanced or retracted through the shell 16. The entire 115 electrode construction may be removed from the chamber for inspection or for making necessary repairs, by moving latch 34 downwardly to disengage the annular shoulder 33 after which the shell 16 may be slid from ring 120 29 and sleeve 19. It should be noted that the limited sliding movement of the shell 16 which permits striking of the arc is independent of the adjustment of the electrode tip 13. In other words, if the correct adjustment is obtained by turning wheel 38, this adjustment will always be reestablished when the shell 16 returns to normal position 125 after striking of the arc.

It will be appreciated that the packed 130

joint between the electrode and non-rotatable head is far removed from the heat of the arc flame. Furthermore if leakage should occur from this joint, it will be exterior and 5 not within the arc chamber.

I claim:

1. In an arc generator, an electrode, means for rotating said electrode, and means for circulating a cooling liquid through said 10 electrode.

2. In an arc generator, an electrode, means for rotating said electrode, means for permitting longitudinal movement of said electrode and means for circulating a cooling 15 fluid through said electrode.

3. In an arc generator, an electrode, means for axially rotating said electrode, means for adjusting the position of said electrode, and means for circulating a cooling fluid through 20 said electrode.

4. In an arc generator, an electrode, means for rotating said electrode about its axis, means for adjusting the position of the electrode in an axial direction, means for temporarily shifting the position of the electrode 25 without affecting said adjustment and means for circulating a cooling fluid through said electrode.

5. In an arc generator, an electrode rotatable about its axis, a stationary electrode, means for permitting limited movement of the rotatable electrode towards the stationary electrode, means normally biasing said rotatable electrode to a position remote from 35 the other electrode, means for adjusting the normal position of the rotatable electrode and means for circulating a cooling fluid through said rotatable electrode.

6. In an arc generator, a hollow electrode, 40 means for rotating said electrode about its axis, and a tube extending into said electrode for conveying cooling fluid to the same.

7. In an arc generator, a hollow electrode, means for rotating said electrode about its

axis, and a stationary tube extending into 45 said electrode and terminating near the end of the same for conveying cooling fluid to the electrode.

8. In an arc generator, a chamber, a rotatable sleeve journaled to said chamber, motor 50 means for driving said sleeve, an electrode removably inserted through one wall of the chamber and adapted to be rotated by said sleeve, and means for passing a cooling fluid through the electrode. 55

9. In an arc generator, a hollow electrode adapted to extend through the wall of a chamber, a relatively stationary head secured to the outer portion of the electrode, said head having passageways for introduction and removal of cooling fluids from the interior of the electrode, and means for rotating said electrode about its axis. 60

10. In an arc generator, the combination of a hollow electrode inserted through a wall of a chamber, means for continuously rotating said electrode, means for adjusting the distance which said electrode projects into the chamber, means for quickly sliding the electrode in an axial direction, means for returning the same against a fixed stop, and means including a non-rotatable head for introducing cooling fluid into and removing it from the interior of the electrode. 65

11. In an arc generator, the combination of a rotatable hollow electrode extending through the wall of a chamber, a non-rotatable head attached to said electrode, said head having passages for introduction and removal of cooling fluid from the interior of 80 the electrode, and a fluid tight joint between the electrode and head, said joint being disposed to discharge leakage exteriorly of the chamber. 75

In testimony whereof, I have hereunto set 85 my hand.

HANS OTTO STORM.
